SOUND MODIFIER

Charles Huenlich, Bloomfield, N. J., assignor to
Thomas A. Edison, Incorporated, West Orange,
N. J., a corporation of New Jersey

Application November 10, 1942, Serial No. 465,129

3 Claims. (Cl. 274—27)

This invention relates to sound modifiers for acoustical-type reproducing phonographs, and is especially concerned with sound modifiers for phonographs which are adapted for transcribing speech recordations made by commercial dictating machines.

Commercial dictating machines of both the acoustical and electrical type have generally had a relatively low signal response in the upper frequency range, particularly in the frequency range containing the higher sibilant sounds, these being the primary sounds imparting intelligibility to one's speech. On the other hand, the usual record materials have a surface noise characteristic which rises with frequency—i. e., wherein the higher frequency components have the higher magnitude. Typically, this record surface noise reaches a level comparable to that of the recorded signal in the higher frequency range above mentioned. There will however be variations, as between machines and different record materials used, in the frequency at which the signal and noise components reach comparable levels. Because of these relationships between the recorded signal and surface noise levels, there has been a distinct need for a fine adjustable control of a particular character over the frequency response characteristic of dictation-transcribing machines, this being particularly so for the higher frequency range mentioned in order that there may be obtained the best balance between recorded signal and noise level to give the maximum accuracy in speech intelligibility.

It is an object of my invention to provide an improved sound modifier that will fulfill the need above expressed.

Other objects are to provide improvements in structure and arrangement for sound modifiers of conventional design, which will permit the reproduction of speech recording with improved quality and intelligibility; and to provide an improved sound modifier which is especially adapted for use in connection with acoustical-type machines for transcribing dictation.

Other and allied objects of my invention will more fully appear from the following description and the appended claims.

In the description of my invention reference is had to the accompanying drawing, of which:

Figure 1 is an elevational view, with a portion broken away, of an acoustical-type reproducing device to which the sound modifier of my invention is applied;

Figure 2 is a vertical sectional view of my sound modifier; and

Figure 3 is a horizontal sectional view taken substantially on the line 3—3 of Figure 2.

In Figure 1 there is shown an acoustical-type sound reproducing device 1 of conventional design, having a hollow circular casing 2 provided with a central tubular neck 3 at the top and with a depending lug 4 at the front. This casing is closed at the bottom, by a diaphragm (not shown), to form a sound chamber therewithin. Below the casing there is a weight 5 having a universal pivotal connection to the lug 4, the weight having a pivotal connection 6 on a vertical axis to a bifurcated arm 7 and this arm having a pivotal connection 8 on a horizontal axis to the lug. The weight 5 pivotally carries a lever 9 into one end of which there is mounted a reproducer stylus 10, the other end of the lever being connected by a link 11 to the diaphragm aforementioned. Under the influence of the weight 5, and of a torsional spring 5' between the lug 4 and arm 7, the reproducer stylus is held in coaction with a record R, which may typically be a wax-like record of cylindrical form as is fractionally shown. Thus, vibrations imparted to the stylus by the record are transmitted to the diaphragm aforementioned, and the vibration in turn generates corresponding sound vibrations in the sound chamber of the reproducing device.

These sound vibrations are transmitted from the tube 3 of the casing 2 to a flexible tubing 11 which it will be understood connects to a suitable ear cap or head set not shown. Interposed between the flexible tubing and reproducer 1, however, is a sound modifier 12 which is adjustable 30 to different settings by a knob 13 at the top as is now explained.

This sound modifier—which in its general structural arrangement is of conventional design—comprises a tubular housing 14 which is retained to the tube 3 of the casing by a set screw 40 15. This housing has a reduced-diameter bore 16 in its upper portion, as is shown in Figure 2, which has an outlet opening 17 at the side in communication with the flexible tubing 11 by way of a tubular extension 18 on the housing. Rotatably fitting the bore 16 is a cylindrical valve member 19 which has a flanged head 20 at the top seating on the housing 14; this flanged head is covered by a knurled insulating piece to form 45 the knob 13 aforementioned. To the lower end portion 19' of this cylindrical valve member there is keyed a washer 21 which is held to the valve member by a nut 22. This washer slidably engages a shoulder 23 within the housing to retain 50 the cylindrical valve member in place. The valve

member is thus rotatable by the knob 13 but its rotation is typically limited to an angular movement of about 180° by a stop pin 13' provided on the knob 13, which stop pin engages a suitable slot provided in the wall of the housing 14 as is shown in Figure 2.

This cylindrical valve member has a central chamber 24 extending from the bottom to near the top thereof and leading from this chamber at a small distance from the top thereof, is a series of graduated openings 25 which are movable selectively into alignment, or into registration, with the side outlet opening 11 by turning the valve member relative to the housing 14. There may, for example be provided five of these openings within a 180° angular interval about the valve member, the succeeding ones of which, proceeding in a counterclockwise direction about the valve member, have increasingly larger cross-sectional areas, as is shown in Figure 3. By selectively setting the knob 13 one or another of the openings 25 is placed into registration with the outgoing tube 18, and sound will be communicated from the reproducer 1 by way of the central chamber 24 and that selected opening to the tubing 11. By moving a larger or smaller one of the openings 25 into registration with the outlet tube 18, the volume of sound transmission from the reproducer is increased or decreased; in addition, there is obtained a frequency discriminating action in the sound transmission from the reproducer, which is of the character of increasingly attenuating the low-frequency sounds, relative to the high-frequency sounds, as smaller ones of the openings 25 are brought into registration with the side outlet opening. The change in modification from one setting to the next is however not discontinuous, but gradual, for the internal diameter of the outgoing tube 18 is equal substantially to the displacement, along the periphery of the valve, between centers of successive ones of the openings 25, and will thus bridge adjacent openings when the valve is midway between settings.

It is in practice also found desirable to provide sound modifiers such as is above described with a leak vent. This venting is had in the present case through a hole 26 provided in the housing 14 and through a hole 27 provided in the valve member, there being an annular groove 28 in the valve member for maintaining communication between these holes when the valve member is adjusted to its different angular positions.

Sound modifiers of the form above described have proven to be very beneficial in enabling the operators of transcribing machines to so adjust the tonal quality and sound volume of reproduction, particularly in relation to the record surface noise, as to obtain an improved accuracy in speech transcription. I have found though that the operation of these modifiers for the particular purpose herein considered may be markedly improved by very simple means. This improvement is had simply by providing a sound-damping medium within the sound chamber 24 of the modifier, particularly in the chamber above the graduated openings 25, the damping medium being provided in effect as a wall portion of this chamber. For instance, as a preferred embodiment,

the chamber 24 is extended well above the graduated openings 25, and this upper portion of the chamber is filled with a thick cylindrical body 29 of sound-damping material. I find for example that corn pith is a very suitable medium for this damping body. As so provided, it is found that the sound modifier enables an operator to obtain a much more desirable tonal balance of speech reproduction, with a less apparent surface noise and an improved intelligibility.

While the embodiment herein shown is a preferred one of my invention, it will be understood that I intend no unnecessary limitation of my invention thereto, for the same is subject to changes and modifications without departure from the scope of my invention, which I endeavor to express according to the following claims.

I claim:

1. In a sound modifier of the character described: a tubular housing having a sound inlet opening at one end and a sound outlet opening in a side wall thereof; a valve member closing the other end of said housing member and forming a sound chamber within the housing member between the inlet and outlet openings thereof, said valve member being rotatably mounted in said housing member and cooperating with said outlet opening to open and close the same upon angular adjustment of the valve member; and 20 a sound-absorptive material lining a wall portion of said sound chamber, said material being exposed to the sound waves in said chamber for direct sound absorption, and the area of exposure of said material being the same in all adjusted 25 positions of said valve member.

2. A sound modifier for acoustical-type reproducing phonographs adapted for transcribing dictation, comprising a housing member having inlet and outlet openings, an adjustable valve member 40 in said housing member having a chamber therein in communication with said inlet opening of the housing, said valve member having a series of graduated openings leading from points in said chamber at a distance from the closed end thereof, said graduated openings being selectively registerable with said outlet opening by an adjustment of said valve member; and a body of damping material at the closed end portion of said chamber beyond said graduated openings, said 45 damping material having a substantial surface thereof exposed within said chamber for direct sound absorption.

3. In a sound modifier including a housing member having inlet and outlet openings: the 55 combination of a hollow valve member adjustably mounted in said housing member for controlling the transmission of sound from said inlet to said outlet openings; means providing leak venting from within said valve member to the 60 outside in each adjusted position of the valve member; and sound-damping means in said valve member, said damping means being placed outside the path of sound travel through the valve member to said outlet opening of the housing member and having a substantial surface thereof exposed within said valve member for direct sound absorption.

CHARLES HUENLICH.
